UNITED STATES PATENT OFFICE.

JOSEPH FOSSEL, OF GRAFTON, MASSACHUSETTS, ASSIGNOR TO ALSATIAN MACHINE WORKS, LIMITED, OF BOSTON, MASSACHUSETTS, A CORPORATION OF MASSACHUSETTS.

COMBING MACHINE.

1,416,951.

Specification of Letters Patent. Patented May 23, 1922.

Application filed January 15, 1921. Serial No. 437,423.

To all whom it may concern:

Be it known that I, JOSEPH FOSSEL, of Grafton, in the county of Worcester and State of Massachusetts, a citizen of the 5 United States, have invented a new and useful Improvement in Combing Machines, of which the following is a specification.

My invention relates to an improvement in combing machines of the character described in Letters Patent of the United States No. 1,351,076, granted on the application of Harry Tunstall August 31, 1920, and it relates more particularly to the means for oscillating the nipper frames whereby 15 each frame will normally take exactly the same period of time to move from its point of rest to its detaching rolls and back, thus enabling the two sides of the comber, when operating on the same grade of cotton, to 20 turn out products of the same grade and with a substantially equally small amount of waste.

In combing machines of the Heilman type the combing cylinder is set in a particular 25 position on its shaft and the movements of the nippers and the piecing-up or detaching rolls are timed so that they may co-operate properly therewith. In a machine like that described in the patent above referred to in which a plurality of combing heads are set back to back and arranged to be operated by a single operating unit, a 30 combing cylinder and detaching rolls are provided for each nipper mechanism, each 35 combing cylinder being mounted as shown in the said patent on a constantly rotating shaft 63 and the detaching rolls being oscillated by mechanism connecting them with shaft 63 through a gear system comprising 40 gears 114, etc., and a clutch. The nipper mechanisms are oscillated alternately and the combs and detaching rolls are set to be operated in opposed relation to each other. The means for oscillating the nipper mechanisms, as shown in that patent, comprises 45 a lever 12 hung on the shaft 13 and swung by connections including a crank pin 10 on disk 9. This results in an approximately accurate motion being given to the bowl 37 50 carried by the rocker arm 36 fast on shaft 13, which bowl as the shaft is rocked engages alternately the nippers 32 and oscillates them.

In view of the minuteness of the cotton 55 fibre it is necessary, however, that each

nipper frame in turn should arrive at its outward position at the moment when the comb on that side of the machine has reached a predetermined point in its movement, and the detaching or piecing-up rolls 60 are at a particular position in their cycle of operations. It has been found that the connections between the crank pin and the shaft 13 for operating the two sides of the machine are not sufficiently accurate always 65 to produce on each side of the machine a product of equal value, because the piecing on both sides will not be equally good without reorganizing the machine or using a different timing for the detaching rolls on 70 one side from the timing of those on the other side.

My invention relates to means other than those shown in the said Letters Patent connecting the power shaft with the bowl 37 75 whereby a more accurate result will be accomplished and it will be understood by reference to the drawings where it is shown in its preferred form.

Figure 1 is a cross section of a head such 80 as is shown in the said patent and embodying my invention.

Fig. 2 is a longitudinal detail showing my improved mechanism and its connections in enlarged side elevation. 85

Figs. 3 and 4 are enlarged sections on lines 3—3 and 4—4 of Fig. 1.

As the machine as a whole is fully described in said Letters Patent, I shall not describe it in detail except in so far as it 90 is necessary to point out my improvement in its preferred form.

In the drawings:—
13 is the shaft to be rocked. It carries near each end an arm 36 at the lower end 95 of which is the bowl 37. One only of these arms is shown 32 are the nipper frames which are engaged by the bowls 37 on the end of the arms 36 and are swung as the arms 36 rock with the shaft 13. 62 are 100 combs on cylinders mounted to rotate with shafts 63 in the directions indicated by the arrows.

On the shaft 13 is mounted a pendulum lever 12 by means of which and the plate 105 14, lugs 16 and screws 15 the shaft is oscillated. 8 is the power shaft carrying the crank disk 9 in the slot 9^a in which is adjustably mounted the crank pin 10.

On a portion of the frame A are mounted 110

supports B, B, which carry two parallel rods C fast thereto to serve as guides for the carriage D. This carriage comprises four sleeves d connected together so that the carriage may be reciprocated horizontally across the machine. The carriage D has vertical ways D¹ in which is mounted a block D² with a hole through it in which lies the crank pin 10. This construction is such that as the crank disk 9 rotates, carrying with it the crank pin 10, the block D² will slide vertically as occasion requires in the ways D¹ while the horizontal movement of the crank pin 10 will cause the carriage to travel horizontally on the rod C. In order that this movement may be applied to the pendulum lever 12, the carriage D carries a pin E free to turn in a block E¹ which slides vertically in the forked end e of the lever 12.

Thus the rotation of the crank disk 9 will cause a lateral swinging or oscillating movement to be given to the lever 12 and shaft 13,—a movement which is positive and which has positive limitations and consequently gives a positive outward movement to the nipper frames, allowing each in turn to swing back into its vertical position in which position its screw 321 engages the stop 642.

d¹ and e¹ are openings for lubrication.

While I have described above the simplest method of accomplishing the desired result, I do not mean to limit myself to the precise construction shown, the purpose of which is to secure a positive means whereby in a duplex comb of this class the nipper frames on both sides of the machine may be timed to co-operate with the combs with equal precision so that there will be turned out from the heads on both sides of the machine a product of equal character in all respects and for this purpose give to each nipper frame on both sides of the machine a movement which shall be equal both in point of time and extent with every other.

What I claim as my invention is:—

1. In a machine of the kind described, in combination with the nipper mechanisms, means for operating them alternately com-

prising a rock shaft, an arm mounted to rock therewith and adapted to engage and operate said nipper mechanisms, and means for rocking said rock shaft comprising a crank disk, a crank pin thereon, a pendulum lever mounted on said rock shaft, and means connecting said crank pin and said pendulum lever whereby said lever will be given an oscillation equal in regard to time and amplitude in each direction about said rock shaft.

2. In a machine of the kind described, in combination with the nipper mechanisms, means for operating them alternately comprising a rock shaft, an arm mounted to rock therewith and adapted to engage and operate said nipper mechanisms, and means for rocking said rock shaft comprising a crank disk, a crank pin thereon, a pendulum lever mounted on said rock shaft, and means connecting said crank pin and said pendulum lever whereby said lever will be given an oscillation equal in regard to time and amplitude in each direction about said rock shaft, said means comprising a carriage, means for connecting said crank pin and said carriage, means for guiding said carriage to move in a straight line and connections between said carriage and said lever.

3. In a machine of the kind described, in combination with the nipper mechanisms, means for operating them alternately comprising a rock shaft, an arm mounted to rock therewith and adapted to engage and operate said nipper mechanisms, and means for rocking said rock shaft comprising a crank disk, a crank pin thereon, a pendulum lever mounted on said rock shaft, and means connecting said crank pin and said pendulum lever, said means comprising a carriage, guideways for said carriage, a block mounted to slide vertically in said carriage and movably connected to said crank pin, and a second block turnably mounted on said carriage, said lever having a fork at its lower end in which said last-named block may slide.

JOSEPH FOSSEL.
